UNITED STATES PATENT OFFICE

2,233,900

ELECTRICAL SWITCH

Fred H. Rowe, Gloucester, Mass., assignor of one-fourth to George W. Hooper, Salem, Mass.

Application February 6, 1940, Serial No. 317,470

2 Claims. (Cl. 200—80)

My present invention relates to switches and more particularly to mercury switches operating on a centrifugal principle whereby the rotation of the switch element causes an electrical circuit to be opened or closed, as the case may be.

The principal object of my present invention is an improved electrical switch;

Another object is an improved electrical switch which operates automatically;

Still another object is an improved electrical switch which operates automatically by means of centrifugal force;

And still another object is an improved electrical switch which operates automatically by means of centrifugal force in which a movable contact element is centrifugally forced away from the contact members and held against return or further agitation while the apparatus is in high rotational speed, and

Other objects and novel features comprising the construction and operation of my invention will be apparent as the description of the same progresses.

In the drawing illustrating the preferred embodiment of my invention:

Fig. 1 is a side elevation of the apparatus, as viewed apart from connecting apparatus;

Fig. 2 is a cross-section taken on the line 2—2 of Fig. 1 showing the internal details and also showing a simple electrical diagram with connections to the contact ends of the apparatus as used in actual assembly;

Fig. 3 is a cross-section taken on the line 3—3 of Fig. 2, and

Fig. 4 is a side elevation of the rotator element removed from the outer casing and particularly showing, in dotted lines, the mercury cavity in the rotor, as viewed at ninety (90) degrees from the showing in Fig. 2.

Referring more in detail to the drawing, 10 indicates a casing. On the top of the casing I have inserted a bushing member 11 which is held in place in the casing 10 by means of the screws 12. Any other method of securing these elements is acceptable.

On the bottom of the casing 10, I have inserted an insulated member 13 with which I have provided a bushing 14, the outer end of which is provided with threads for the purpose of receiving a male member.

Passing through the bushing 14, I have shown a shaft 15. Passing down through the bushing 11 I have shown another shaft 16. The opposed ends of the shafts 15 and 16 are imbedded in an insulated member 17. Separating the two op-

posed ends of the shafts 15 and 16 is an insulating medium, such as mica or the equivalent, as indicated in elevation at 18.

The rotor 17, is preferably made from moulded material and is provided with spiral recesses 19 and 20, the top being sealed by means of a cover member 21. This cover member may be held in place, sealed, or otherwise secured in any suitable manner.

The recesses 19 and 20 in the rotor 17 comprise spiral tracts, shown at 22 and 23 respectively. As viewed in Fig. 4, the vertical lines 19 and 20 show the deep end of the recesses 19 and 20 with respect to their back vertical sides. The recesses terminate at the surface of the rotor 17 under the cover 21. The numerals 22 and 23 indicate the spiral bottom surface of these recesses.

At the lowermost portion of the tracts, or bottom surfaces of the recesses, a passage is provided directly to the insulated shafts 15 and 16, such that an area of the shaft ends is bared on either side connecting with the recesses in the rotor.

In the recesses, I have deposited a certain amount of mercury which forms a rolling flexible ball, as indicated at 24 and 25.

At 26, I have indicated the rear stop light of a motor vehicle. 27 indicates the cable leading to a speedometer of said motor vehicle. 28 indicates the cable leading to the transmission or other positive elements of the motor vehicle which control the traction elements of said vehicle.

At 29, I have indicated a battery, one of which electrical poles connects with a common ground 30.

At 31, I have shown a simple switch, preferably mounted on the control panel of an automobile.

In operation, assuming that the switch involving the present invention is associated with the stop light of an automobile, and the panel switch 31 has been closed for evening driving, the cable drive from the transmission of the vehicle or from other parts, as the wheels, rotate the shaft 16. As the rotor 17 speeds up, the centrifugal force throws the mercury members 24 and 25 outward in the tracts 22 and 23. The mercury balls roll up the inclined tracks 22 and 23 to the highest point and remain there while the rotor 17 is revolving at high speed. When the vehicle slows down and the rotor 17 decreases its speed to a predetermined degree, the mercury balls 24 and 25 return by means of 55

gravity and contact the two opposed ends of the shafts 15 and 16 bridging the insulating material 18 which separates the shaft ends. In this position, and assuming that the dash switch 5 31 is in a closed position, the circuit through the tail light lamp is completed and the tail light is illuminated.

When my switch is applied to the tail light of a motor vehicle it will be apparent that when 10 the vehicle is traveling at normal speed on a highway, the stop light will not be illuminated but in the event that the driver slows up to make a stop or to make a turn, the tail light will become illuminated regardless of whether or not 15 the driver has used his foot or emergency brake.

A very important element of my invention lies in the inclined tracks 23 and 22 because it is necessary that the mercury balls 24 and 25 remain fixed at the upper ends of such tracks with 20 respect to the tracks themselves. By this I mean that the mercury is prevented from becoming broken up into a multiplicity of small balls as is the case where a cup shaped cavity is used. Such a break up of the mercury in a cup shaped 25 recess is due to the fact that the surface of a cup races around under the mercury more or less without rotating the mercury with it. These fine

particles of mercury having a much lesser weight settle back and close the circuit between the two shafts or other contacts defeating the purpose of the device.

Having thus described my invention what I 5 claim as new is:

1. An electrical centrifugally operated mercury switch comprising, an insulated rotor having a contact shaft mounted in each end, the opposed ends of said shafts being insulated from each other, a recess located in said rotor having an inclined closed spiral track, the lower end of said track terminating at the insulated ends of said shafts, a ball of mercury located in said recess and rolling on said track, a casing supporting said rotor and journals for said rotor to revolve on.

2. In an electrical centrifugally operated mercury switch, an insulated rotor having a shaft at either end journaled in a casing, the opposed ends of said shafts located with said rotor being insulated from each other, an internal closed recess in said rotor having a bottom track comprising a spiral groove, the lower end of said track engaging with the exposed ends of said 25 shafts, a mercury ball located in said recess.

FRED H. ROWE.
